DESIGN FOR A CLOTHES HAMPER

Jack J. Kohen, South Bend, Ind.

Application October 19, 1944, Serial No. 115,865

Term of patent 14 years

(Cl. D58—4)

To all whom it may concern:

Be it known that I, Jack J. Kohen, a citizen of the United States, residing at South Bend, in the county of St. Joseph, State of Indiana, have invented a new, original, and ornamental Design for a Clothes Hamper, of which the following is a specification, reference being had to the accompanying drawing, forming part thereof.

Fig. 1 is a front perspective view of the clothes hamper showing my new design.

Fig. 2 is a front perspective view of the hamper with its lids raised.

I claim:

The ornamental design for a clothes hamper, as shown.

JACK J. KOHEN.
